UNITED STATES PATENT OFFICE.

CHARLES F. MOSMAN, OF BRIDGEPORT, ASSIGNOR TO THE LANDERS, FRARY & CLARK, OF NEW BRITAIN, CONNECTICUT.

DESIGN FOR A CUTLERY-HANDLE.

SPECIFICATION forming part of Design No. 22,484, dated May 30, 1893.

Application filed May 1, 1893. Serial No. 472,615. Term of patent 7 years.

To all whom it may concern:

Be it known that I, CHARLES F. MOSMAN, a citizen of the United States, residing at Bridgeport, in the county of Fairfield and State of Connecticut, have invented and produced a new and original Design for Cutlery-Handles, of which the following is a specification, reference being had to the accompanying drawings, forming part thereof, in which—

Figure 1 is a side elevation of a cutlery handle showing my design. Fig. 2 is a plan view of the same.

A designates the body of the handle, B the ornamental tip or butt, and C the ornamental portion of the ferrule end of the handle. The contour of the parts is fully shown in the two

figures of the drawings. The ornamental tip or butt B is ornamented with leaflets and scrolls arranged as shown, and the ferrule end is ornamented in harmony therewith. Its ornaments are divided into two portions by the plain bands *ab*. The drawings so clearly show the design that a further description is considered unnecessary.

What I claim is—

The design for cutlery handles, substantially as herein shown and described.

CHARLES F. MOSMAN.
